PRE-CAST CONCRETE PAVING BLOCK

Matthew Robert Fenton, 6010 Centre,
Pittsburgh, Pa. 15206

Filed June 23, 1967, Ser. No. 7,578

Term of patent 14 years

(Cl. D60—1)

Fig. 1.

Fig. 2.

Fig. 3.

Fig. 4.

Fig. 5.

FIGURE 1 is an isometric view of the upper side of my pre-cast concrete paving block;

FIGURE 2 is an isometric view of the lower side of my pre-cast concrete paving block;

FIGURE 3 is a lower left side elevational view of the block as shown in FIGURE 1;

FIGURE 4 is a lower right side elevational view of the block as shown in FIGURE 1;

FIGURE 5 is an upper right side elevational view of the block as shown in FIGURE 1.

I claim:

The ornamental design for a pre-cast concrete paving block, substantially as shown and described.
